UNITED STATES PATENT OFFICE.

NORWOOD H. KNOWLTON, OF ROCKPORT, MASSACHUSETTS, ASSIGNOR TO UNITED SHOE MACHINERY CORPORATION, OF PATERSON, NEW JERSEY, A CORPORATION OF NEW JERSEY.

ASSEMBLING MACHINE.

Application filed December 6, 1919. Serial No. 342,935.

This invention relates to machines for operating on boots and shoes and particularly to machines for assembling parts of boots and shoes upon their lasts preparatory to the pulling over and lasting operations. For the purpose of illustration an embodiment of the invention is herein shown as applied to a machine of the type disclosed and claimed in United States Letters Patent No. 1,356,510, granted October 26, 1920, on application of Orrell Ashton; No. 1,443,288, granted January 23, 1923, on application of W. C. Stewart; and in No. 1,541,823, granted June 16, 1925, on my prior application.

An object of this invention is to improve and perfect machines of this type while retaining all the valuable and desirable features disclosed in the above-mentioned Letters Patent.

Machines of this type as previously organized are provided with a work support which is movable into and out of operative relation to the machine, the shoe being depressible against a light spring until the machine starts, whereupon the shoe is held against movement both downwardly and outwardly of the machine. Such prior machines are also equipped with a wiper which moves over the shoe bottom to wipe the upper at the rear end of the shoe against the shoe bottom, tacking means to secure the upper in position, and a gripper co-operating with the wiper to tension the upper prior to the action of the wiper. The wiper and gripper, after the upper is seized, first move upwardly to tension the upper and then downwardly and forwardly to lay the upper against the bottom of the shoe. The gripper having let go, the wiper and gripper move upwardly, rearwardly and downwardly to normal position. The gripper, being now open and lying just over the secured upper, is in such a position that, as the shoe is withdrawn, the secured upper may catch on the gripper and be torn loose, particularly since the last raising spring has a tendency to raise the shoe during its movement out of the machine.

A feature of the present invention consists in means for effecting vertical separation between the shoe and the wiper and gripper and holding the shoe and gripper in such spaced relation when the machine stops to prevent the secured upper from

catching on the gripper when the shoe is withdrawn. Preferably and as shown herein, the wiper and gripper are raised relatively to the shoe and are restored to normal position for the next operation as an incident to the removal of the shoe from the machine. For this purpose connections are provided between the shoe support and the wiper to restore the wiper to normal position when the work support is moved away from the machine.

Another feature of the invention consists in means for causing the gripper to close after it has released the upper and is raised and moved rearwardly. Hence the gripper is closed as it passes rearwardly over the wiped over and secured margin of the upper, and is caused, when lowered just as the machine stops, to rest on the wiped over portion of the upper with its jaws at the rear of the edge of the inturned margin so that there is no tendency for it to catch on the secured portion of the upper when the shoe is withdrawn. This construction contributes to the same result as the feature first above mentioned and, in fact, under certain conditions either of these constructions may be used without the other with advantage. Of course if both constructions are provided the gripper will remain raised as well as closed until the shoe is withdrawn.

The machine of the Letters Patent above referred to is provided with tackers to secure the flange of the counter at the corners of the heel seat. It is desirable that the counter flange be forced downwardly flat against the shoe bottom prior to its being secured in place. Accordingly a feature of the invention consists in means associated with each of the flange tackers for forcing the counter flange against the shoe bottom prior to its being secured in position. As shown herein, a presserfoot is secured to each of the tacker members and has its pressing face located longitudinally of the shoe slightly forwardly of the tacker and in a plane below the nozzle or tack fingers of the tacker. By this construction the tack fingers are prevented from coming into actual contact with the work and are hence free to open to allow passage of the tack and driver.

In the patent second above referred to, a construction is disclosed in which the tackers are yieldingly pressed against the counter

flange prior to the insertion of the tacks. A feature of this invention consists in means for effecting movement of the tackers to cause the pressers to force the upper against the shoe bottom positively. As shown herein in the means for operating the gripper acts through suitable connections to cause the tackers to descend positively to bring the tackers to tacking position and to force the pressers against the shoe bottom.

In machines of prior construction a tack is driven early in the cycle of the machine through the margin of the counter which is adjacent to the crown of the last and another tack is driven into the rear end of the last adjacent to the heel seat simultaneously with the driving of the tack which holds the upper and counter to the innersole at the rear end of the heel seat, tacks also being driven through the counter flange inside the upper at this time. A feature of the present invention consists in an organization for operating the driver of the upper rear end tack after the driving of the tack into the margin of the counter adjacent to the crown of the last and prior to the driving of the vertical tack into the rear end of the heel seat and also prior to the driving of the counter flange tacks. Preferably the upper rear end tack driver is operated when the action of the wiper is nearly completed and just prior to the descent of the pressers to force the counter flange against the shoe bottom. The blow of the upper rear end tack driver is delivered not only against the tack, if there is a tack to be driven, but also against an abutment slide through which the tack is driven. This blow acts therefore to seat the counter against the rear end of the last adjacent to the heel seat to assist the wiper in the wiping in of the stock and to put the counter in better position for the action of the pressers and for the securing of the parts by the tacks which are driven vertically after the action of the pressers. Usually, of course, a tack is driven by the upper rear end tack driver, but the blow is effective, as stated, whether or not it drives a tack and in some instances the upper rear end tack is unnecessary and undesirable and is hence omitted.

Other features of the invention consist in means for preventing the vertically driven tacks from jumping back into the delivery passages during rapid operation of the machine, improved means for adjusting the tension of the side pressers, and means for varying the position lengthwise of the shoe of the counter tacks relatively to the rear heel seat tack.

These and other features of the invention, including various novel constructions and combinations of parts, will appear more fully from the following description when read in connection with the accompanying

drawings and will be pointed out in the appended claims.

The novel construction and arrangement of tack holding fingers herein shown and described but not claimed is being claimed in a divisional application Serial No. 208,935, filed July 28th, 1927.

In the drawings,

Fig. 1 is a side elevation of the machine, partly in section;

Fig. 2 is a front elevation, partly in section, of the counter tacker mechanism;

Fig. 3 is a detail view of parts shown in Fig. 2;

Fig. 4 is a view, partly in section, of a friction pin for holding parts of the machine in place;

Fig. 5 is a view, partly in section, of a modified form of the pin shown in Fig. 4;

Fig. 6 is a front elevation of the upper portion of the machine;

Fig. 7 is a perspective view of a portion of the mechanism for operating the side pressers;

Fig. 8 is a detail view of parts shown in Fig. 6;

Fig. 9 is a detail view of parts shown in Fig. 8;

Fig. 10 is a sectional view of the gripping, wiping and rear end tacking mechanisms;

Fig. 12 is a view in perspective showing the counter tacker fingers;

Fig. 13 is a perspective view of the spring shown in Fig. 12;

Fig. 14 is a sectional view showing the gripper closed and operated to tension the upper;

Fig. 15 is a view similar to Fig. 14, showing the operation of wiping in the upper;

Fig. 16 is a perspective view of the mechanism for holding the wiper in raised position;

Fig. 17 is a side elevation of parts shown in Fig. 16;

Fig. 18 is a perspective detail of one of the driver cams;

Fig. 19 is an exploded view, in perspective, of one of the rear end tacker mechanisms;

Fig. 20 is a sectional view in assembled position of the parts shown in Fig. 19;

Fig. 21 is a plan view of the upper rear end tacker mechanism; and

Figs. 22 and 23 are sectional details of parts shown in Fig. 21.

The drawings represent a machine embodying the present invention which, except as to various mechanisms which are fully described herein, is of a construction similar to that disclosed in the Letters Patent to which reference has been made above.

The numeral 2 (Fig. 1) indicates the frame of the machine head which is secured to a column 3. The slides or abutments of

the upper and lower rear end tacking mechanisms are indicated respectively by the numerals 4 and 6 and the reciprocating wiper carrier by the numeral 8, the latter being mounted on a carrier slide 9 and having pivoted thereon a gripper member 7 which co-operates with the wiper to seize and tension the upper. The tacks for the various tacking mechanisms, including the counter tackers and the tacker which inserts a tack in the rear end of the heel seat, to be described, are supplied from a tack pot 10 by tack separators located at 12 through suitable tubes, the tack drivers being operated by cams on the main shaft 11. A depressible jack post 14 is locked against outward movement and against depression by the action of a hook 16. Side pressers 18 and 20, which are operated by springs 22, press against the sides of the rear portion of the sole and are released by contact of the hook 16 with the arm 24 of a bell crank lever, the other arm 25 of which effects movement of the pressers away from the shoe and places the springs 22 under tension.

The jack post 14 is yieldingly supported by a spring 26 and mechanism like that disclosed in my prior Letters Patent above mentioned is provided for depressing the jack post as it is swung into the machine to insure that the jack, as it is swung about its pivot 13 toward the machine with a shoe upon it, will be depressed and then allowed to rise so that the upstanding margin of the upper 35 at the rear end of the shoe is lowered while passing the gripper member 7, and is allowed to rise when positioned vertically between the wiper 8 and the gripper 7. For this purpose the post 14 carries a latch 28 pivoted thereto by a screw 30 to turn in a clockwise direction against a spring 32 and arranged to engage a cam face 34 on an arm 36 which is adjustably secured to the machine frame. When the jack is swung 45 toward the machine the latch 28 engages the inclined cam face 34 of the arm 36 and the post is depressed until the latch reaches the vertical portion of the cam face, whereupon the post is raised by the spring 26. When the post 14 and shoe are swung outwardly the latch 28 swings against the spring 32 to allow outward movement of the jack without depression. When a shoe is mounted upon the post 14 and swung into the machine it will be depressed by the mechanism described and allowed to rise so that the upstanding margin of the upper will be positioned behind the gripper 7. The gripper will then rest on the flange of the 55 counter and as movement of the shoe continues will move with the shoe against the light pressure of a spring plunger 33 (Fig. 10) which holds it in normal position. As the inward movement of the shoe continues 60 the rear end of the shoe adjacent to the

crown of the last engages a V-shaped face of the forward tacker slide 6 which is mounted to yield inwardly until the rear end of the shoe adjacent to the heel seat engages the upper tacker slide 4, whereupon the slide 70 4 is moved to actuate a lever 17 (Fig. 1) and cause a pawl 19 to lock the lower tacker slide 6 against movement, mechanism for this purpose being substantially as disclosed in the above-mentioned Stewart patent. A starting 75 treadle 15 is now depressed to start the machine, power being then applied to the shaft 11, rotation of which causes a cam 38 mounted thereon to permit descent of the hook 16 which has an acting face to engage a roll 39 80 on the work support, the face being so contoured that the farther the hook descends the farther into the machine the work support will be drawn. This construction, therefore, takes care of the variation in the 85 lengths of lasts between the end of the last and the pin hole of the last and causes lasts of any length to be firmly clamped against the automatically locked slide 6. In the prior construction the cam which controlled 90 the action of the hook was a drop or precipice cam which allowed the hook to be forced down suddenly with a severe shock which caused the hook sometimes to rebound and release some of the rearward pressure, 95 and the hook was actuated by a torsion spring the tension of which varied considerably with the different positions assumed by the hook because of variations in the 100 lengths of lasts. In the present construction the cam 38 is contoured to allow gradual movement of the hook into position behind the roll 39 of the work support to apply rearward pressure to the shoe and lock the post 14 against depression. The rear end of 105 the hook lever is connected by a rod 40 to one arm of an angle lever 42 pivoted to the frame at 43 and having on its other arm a roll 45 which rests on the cam 38. A long 110 and powerful helical spring 44 (Fig. 1) is connected between the rear end of the hook and a bracket 46 on the frame. By this construction powerful rearward pressure is applied to the shoe irrespective of the amount 115 the hook descends because of different sizes of lasts and the cam allows the pressure to be applied gradually without shock or sudden strain upon the shoe or machine parts and eliminates objectionable noise. When 120 the hook descends a roll on the arm 24 of the bell crank lever pivoted at 23 is released, allowing the other arm 25 to free the arms 50 (Fig. 7) which are fixed to vertical shafts 52 by which the side pressers 18 and 20 are 125 operated.

In the construction embodying the present invention improved mechanism for adjusting the tension of the springs 22 which operate the side pressers is provided. As shown in Fig. 7, collars 54 are mounted one on each 130

of the shafts 52 to one of which the lower end of each spring is secured. The lower faces of the collars 54 are provided with ratchet teeth which engage similar teeth on collars 55 fixed to the rockshafts 52. The collars 54 have capstan holes for the insertion of an implement by which the collars may be turned to vary the tension of the springs. The upper ends of the springs engage lugs 56 on a frame 58 secured to the front of the column 3 and having journals for the shafts 52. This construction affords means for accurately adjusting the inward pressure of each side presser independently.

15 As soon as the shoe has been positioned and held as described by the hook and side pressers, a tack *a* (Fig. 15) is driven through the lower tacker slide 6 into the rear end of the shoe through the upper and the margin 20 of the counter which is next to the crown of the last. The shoe is now ready to be operated upon by the gripper 7 which is actuated by mechanism shown in Fig. 6. An angle lever 60 is pivoted at 62 to a bracket 25 64 secured to the wiper carrier 8 at 66 (Fig. 1). The rear arm of the lever 60 carries a roll 68 which rests against a cam face 70 which is sufficiently wide to allow the roll 68 to be moved radially of the cam by the 30 forward movement of the carrier 8 without its relation to the cam being disturbed. The forward arm of the lever 60 extends transversely of the machine and carries a screw 72 (Figs. 6 and 10) which engages 35 the gripper 7 below its pivot 74. Above the pivot 74 of the gripper 7 is a screw 76 (Fig. 10) which engages the wiper carrier 8 and limits outward movement of the gripper 7. The lever 60 is actuated by a pull spring 78 40 (Fig. 1) connected between the lever 60 and the bracket 64 and normally under tension so that when the cam 70 releases its inward pressure upon the rear arm of the lever 60 the spring 78 will swing the lever 60 inwardly to cause the screw 72 to press inwardly upon the gripper member 7 and cause its lower end to force the upper against a co-operating face 79 on the wiper 8 firmly to hold it (Fig. 14). The cooperating 45 faces of the wiper and gripper are preferably formed with interengaging angular formations which render their gripping action substantially positive. This construction is more fully disclosed in Letters Patent No. 1,541,823 above referred to.

At the time when the gripper operates the upper has not only been secured to the rear end face of the last by the tack *a* driven adjacent to the crown of the last, as explained, 50 but is also held clamped against the now locked lower end tacker slide 6 by the action of the hook 16. The wiper carrier 8 is pivoted at 80 (Fig. 14) to the wiper carrier slide 9 which is guided on rods 81 and 55 is reciprocated by a cam roll 82 engaging

a cam path 83 in a cam block 84 on the shaft 11. The wiper carrier is yieldingly forced downwardly by a spring plunger 86 mounted in the slide 9 and bearing on a shelf 88 on the wiper carrier 8. The cam block 70 84 has a cam face on its periphery coating with a roll 90 on a lever 92 pivoted at 94 to the frame and having on the end opposite to the roll 90 a block 96 pivoted to the lever and adapted to engage the lower face of the shelf 88 on the wiper carrier 8 and to lift it when the roll 90 is engaged by a peripheral projection on the cam block 84. On the cam block 84 are two such peripheral projections 98, 100, the latter having a greater extent peripherally of the cam block than the former.

Referring to Figs. 14 and 15, it will be seen that, after the gripper has closed and before the wiper begins to advance, the projection 98 acts upon the lever 92, causing the block 96 to lift the wiper carrier and of course the gripper 7, thus effecting an upward pull on the upper stock from the point held by clamping pressure and by the lower rear end tack *a* already driven. After the upward pull the projection 98 passes off the roll 90, allowing a wiping face 102 of the wiper carrier 8 to lay the tensioned upper on the heel seat, the wiper meantime being advanced by its cam 83 to maintain tension on the upper. After the wiper has nearly completed its movement and assumed control of the upper the gripper is released (Fig. 15) and the driver of the upper rear tacking mechanism operates to deliver a blow upon the tacker carried by the slide 4 which is transmitted to the counter adjacent to the heel seat to cause the counter to be firmly seated against the last and to drive a tack *b* at this point if such a tack is desired. After the full wiping movement of the wiper has been effected a tack *c* is driven through the wiper in the usual manner by a driver bar 104 operated by a driver lever 106 (Fig. 1) pivoted at 108 to the wiper slide 9 and operated by a cam 109 on the cam shaft 11 of the machine which engages a roll 107 on the lever 106. The projection 100 of the cam 84 acts to raise the wiper and hold it out of contact with the shoe during the return movement of the wiper.

The upper having been tensioned, wiped over and secured at the rear end of the heel seat, the cycle of the machine so far as the action of the parts now being considered is concerned, is completed and the shoe is released for withdrawal from the machine by lifting of the hook 16 and the release of the side pressers 18 and 20. During the removal of the shoe, however, it is desirable that the gripper 7 be prevented from catching on the upper where it has been secured and causing it to be torn loose. To this end a member 120

110 (Figs. 15 and 17) is provided which is secured to the wiper slide 9 at 112 and extends outwardly over a forward extension 114 of the upper end of the gripper 7. As 5 the carrier 8 is raised by the cam projection 100 the extension 114 engages the member 110 which is vertically stationary and hence the gripper is caused to turn on its pivot 74 until it engages the wiper and is held closed 10 until the wiper and gripper have been moved rearwardly so that when the cam projection 100 allows the wiper carrier 8 to descend the gripper will be rearwardly beyond the edge of the secured upper and the shoe may be 15 withdrawn without liability of the upper catching on the gripper.

Preferably, however, mechanism is also provided in the present organization of the machine for maintaining the shoe and wiper 20 in vertically separated relation to avoid any possibility of the upper catching on the gripper. As shown in Figs. 16 and 17, on the forward end of the lever 92, which raises the wiper carrier 8, is adjustably secured a block 25 118 by a bolt 117, a tongue and groove connection between the lever and block being provided to prevent turning of the block. Beneath the block an angle lever is loosely pivoted at 116 on the machine frame and 30 has one arm 119 extending upwardly and carrying a latch plate 120. A rod 122 passes freely through a forwardly extending arm 124 of the angle lever and carries above the arm a split clamp collar 126 threaded thereon for adjustment, and beneath the arm carries respectively fixed and loose collars 128 and 130 between which is a spring 132. The lower end of the rod 122 is pivoted at 134 to the work support above its pivot 13. When 40 the work support is swung toward the machine in presenting a shoe, an upward thrust is imparted to the rod 122 which acts through the spring 132 to swing the latch plate 120 against the forward face of the block 118 (Fig. 16); the spring 132 then yielding during the remainder of the movement of the work support. When the machine has operated and the lever has raised the wiper and gripper away from the shoe (Fig. 17) the 45 latch 120 snaps under the block 118 and prevents descent of the wiper and gripper when the machine stops. With the work support, in this position the pivot 134 of the rod 122 is substantially over the pivot 13 of the work 50 support and hence during the first part of the outward movement of the work support substantially no movement is imparted to the arm 124. This allows the shoe to be moved outwardly beyond any possible contact with the gripper before the later portion of the movement of the work support acts to exert a downward pull on the rod 122 sufficient to withdraw the latch plate 120 from beneath the block 118 and allow the wiper

and gripper to descend to normal position 65 for the next operation.

Referring to Fig. 6, the central tacker through which a tack is driven by the driver bar 104, as described, to secure the wiped over upper, is indicated at 121. On each 70 side of the tacker 121 is a counter tacker frame 123, all three tacker arms being carried, of course, by the wiper carrier 8. In each frame 123 is a driver bar 125 carrying a driver 127 and connected at its upper 75 end to the driver lever 106 which is operated by the driver cam 109. Tack tubes 129 lead into the driver passages at points just below the normal raised position 127' (Fig. 80 3) of the lower end of the driver and are fed before the movement of the wiper and gripper to updraw and overwipe the upper. These movements of the wiper take place very quickly when the machine is running at high speed and it sometimes happens that 85 by this movement the tacks are bounced back partly into the feed passages and are cut off by the drivers as they descend immediately after the upper is tensioned and wiped. This possibility is avoided in the present 90 construction by a formation of the driver cam 109 by which the drivers are lowered far enough to cover the feed openings into the driver passages, for example, to the point 95 shown in full lines (Fig. 3) during the rise 95 and advance of the wiper and are then raised and released. This is effected by the depressed portion of the cam 109 indicated at 131 in Fig. 18. As shown, the portion of the cam face which has no work to do is 100 depressed and left unfinished for the sake of economy in manufacturing the cam. This portion is indicated at 133 in Fig. 18. The roll 107 of the driver lever is prevented 105 from reaching this surface of the cam by the usual buffer washers which arrest movement of the drivers and of the lever 106. Each counter tacker frame 123 is guided at 110 its upper end on its driver bar 125 for vertical movement and at its lower end is guided for movement laterally of the shoe or horizontally by a rod 135 which projects horizontally on each side of the central tacker frame 121. For convenience the description may now be confined to one of the counter tackers, it being understood that the other is similar in construction but has 115 its parts in reversed position. The tacker frame 123 at the right of Fig. 6 is embraced by a member 136 (Fig. 8) which has upward extensions 137 lying at each side of the tacker frame 123 to provide extended surface bearings for the frame. The tacker frame 123 has a slot 138 to receive a roll 120 141 (Fig. 2) on a transverse bolt 139 which 125 passes through holes in the member 136. This construction permits vertical movement of the frame 123 relatively to the mem-

ber 136, the frame being held raised by a spring 140 connected between it and the central tacker 121. To the outer end of the member 136 is secured by a screw 142 a member 144 (Figs. 8 and 9) which has a boss 148 bored to form a long bearing for the rod 135. The members 136 and 144 are formed with tongue and groove connections, as shown, to prevent relative turning of them about the screw 142 and the member 144 is slotted at 146 to permit the tacker frame 123 to be adjusted forwardly and rearwardly of the shoe relatively to the frame 121.

The member 144 has a downward projection 145 having a tongue and groove connection with a roll carrier 150 on which is mounted a roll 152. The roll carrier is slotted to receive a screw 154 by which it is held in adjusted position on the projection 145. The roll 152 engages a cam face 156 (Fig. 11) formed on the side presser 20 which, during movement of the roll forwardly over the shoe bottom, causes the tacker to slide laterally on the rod 135 to position the tacker over the flange of the counter inside the upwardly projecting margin of the upper. The roll 152 may be adjusted properly to position the tacker relatively to the width of the flange by loosening the screw 154 and sliding the roll carrier 150 on the projection 145.

To the lower face of the tacker frame 123 (Figs. 2 and 6) is secured at 158 a presser member 160 having a downwardly and inwardly bent end portion 162 which forms a presser to engage the flange of the counter. The presser is located in a plane slightly below tack fingers 164, 165 (to be described) between which a tack is driven, and enough in advance of the fingers to allow opening of the fingers by passage of the driver between them. Both the tacker frames 123 are of course provided with pressers 162 which are pressed against the flange to force it against the shoe bottom prior to the driving of the counter tacks by the following means, reference being made to Figs. 10 and 11: A U-shaped member 166 is pivoted by holes 168 on extensions of the pivot 74 of the gripper. The inner ends of the member 166 rest on ledges 170 formed on the tacker frames 123. Beneath the pivot 74 the member 166 has a projection 172 which is adapted to be engaged by the head 174 of a stud 176 (Fig. 10) secured to the gripper operating lever 60. When the gripper lever is moved outwardly by the positive action of the cam face 70 to release the gripper, the head 174 engages the projection 172 and turns the U-shaped member 166 on its pivot 74, causing its ends to act on the ledges 170 of the tacker frames and move them downwardly against the springs 140, thereby forcing the pressers 162 against the flange of the counter. This movement also brings

the tack fingers 164, 165 into close proximity to the work without actually touching it; hence the separation of the tack fingers is not interfered with by contact with the work while the fingers are close enough to the work to avoid driving a tack through the air for any material distance.

The lower end of each tacker frame is formed, as shown in Fig. 12, with a reduced rectangular portion 178 which is embraced by lateral extensions 167, 169 from the tack fingers 164, 165, the inner faces of the lateral portions being cut away to form a space 180 to fit the reduced portion 178 of the tacker frame. The fingers are held together by a spring 182 having normally the shape shown in Fig. 13. Grooves 184 are formed on opposite faces of the lateral extensions 167, 169 of the tack fingers to receive the legs of the spring. In assembling the fingers the spring is removed, the fingers separated and placed about the reduced portion 178. The spring 182, while in the shape shown in Fig. 13, is then placed with the end of one of the legs in each of the grooves 184. The loop of the spring is then turned in the proper direction through substantially half a revolution which brings the legs of the spring parallel, whereupon it can easily be pushed again into the position shown in Fig. 12. Since the tack fingers are held together only by the spring 182, they are free to rock when the driver is forced between them about the upper inner corners 186 of the lateral projections. This permits much freer passage of the tack and driver and produces much less wear on the tack fingers than a construction such as that disclosed in the Ashton patent above mentioned, where the tack fingers are constrained to separate in parallel relation. When the spring is removed the fingers are entirely unconnected and hence they can be assembled upon and removed from the machine with great facility; particularly when the spring is arranged as shown with its legs normally crossed, it can, by manipulating it as described, be placed in operative relation to the fingers very easily.

An improved construction of the end tacker mechanism is shown in Figs. 19 to 23. The body or slide 4 of the upper rear tacker is mounted for sliding movement in the machine frame substantially horizontally and a tacker member 190 is pivoted to the slide 4 by a pin 192, uniform in cross-section as shown in Fig. 22. In prior constructions the part corresponding to the pin 192 is in the form of a bolt threaded into the slide 4. These bolts are frequently broken at the weakened threaded portion by reason of the continued vigorous impact therewith of the usual stop collars on the driver bars, which blow is transmitted as described to the slide 4 and to the counter on the last which rests

against the V-shaped outer face of the slide. They are also inconvenient to remove when it is necessary to take out one of the tacker frames for inspection or renewal. In the present construction the pin 192 is provided with a flange 194 having a flat upper face and an upwardly flaring lower face which, as the pin is pushed into position, engages a beveled upper face of a spring latch 196, the flange 194 acting to push the latch back until the latch snaps into position with its flat lower face in contact with the flat upper face of the flange 194, thereby locking the pin in position. When it is desired to remove the pin the latch 196 is pushed back by a handle 200 and the pin pulled out by its head 202. The pin 192 forms a pivot for the tacker frame 190 about which it may be adjusted to vary the position of the tack 4 relatively to the V-shaped face of the slide 4, against which the shoe is pressed, and which acts to centralize the shoe laterally. There is a laterally elongated slot 191 extending through the V-shaped face of the slide 4 through which the tack is driven. This adjustment therefore varies the position of the tack relatively to the back seam of the shoe and is effected by a screw 204 which is threaded through a lug 205 on the tacker frame and bears against a face 206 of the slide 4. A leaf spring 208 is secured at one end to the slide 4 and at its other end bears on the head of the screw 204 to hold the screw against the face 206, the spring 35 also engaging a groove in the head of the screw 204 to hold it from being turned accidentally.

Heretofore the tack fingers of the rear end tackers of this machine have been of very fragile construction and frequent breakage has resulted. In the present construction tack fingers of substantial construction similar in principle to those described for the counter tackers are provided, as shown particularly in Figs. 19 and 20. The forward end of the tacker frame 190 is reduced to form a tack nozzle 210 which extends between two tack fingers 212, 214 formed as shown in the exploded view of Fig. 19. The tack fingers have lateral projections 216, 218 which are cut away at 222 to embrace a rectangular portion 224 of the tacker frame formed to receive them. The projections 216, 218 are positioned one on each side of the portion 224 and a spring 226 is applied with its ends in suitable grooves 288 in the projections, there being depressions 230 in the grooves to receive the inwardly bent ends of the spring yieldingly to hold the spring in position. From Fig. 20 it will be seen that the inner faces 219 of the projections 216, 218 are beveled so that as the driver 232 forces a tack between them they will turn on the inner corners 234 of the projections

against the action of the spring 226 and allow the tack and driver to pass through. By this construction of the tack fingers the tack is guided with certainty and precision, breakage is avoided, and the fingers may be readily renewed when worn. The construction of the lower rear tacker mechanism 6 is substantially similar to that of the upper rear tacker mechanism just described, some of the parts being reversed in position for convenience of access. The tack drivers of the rear tacker mechanisms are operated by separate cams on the shaft 11, the lower driver being operated early in the cycle by a cam 236 (Fig. 1) and the upper driver 232 being operated later and before the vertical tackers by a cam 238.

In Fig. 4 is shown an improved form of friction pin, one of which is utilized to hold a throat block 240 in front of the tack separator 12 (Fig. 1) in position, and another to hold the raceway cover 242 in place, it being desirable that these pins shall be easily removed and inserted to permit the tack passages to be cleared when they become clogged and for separation of the tacks in the raceways. The pin 250 is provided with a nubbed head 252 at one end and at the other end has a slot 254 milled therein which extends along one side of the pin around the end of the pin and along the opposite side of the pin, the slot forming a web 256. The web is provided with a hole 258 and a spring 260 is arranged in the slot extending from a point in the slot near the hole 258 at one side of the pin around the end along the slot on the other side of the pin and having its end extending through the opening 258. On opposite sides of the pin the spring 260 is bent outwardly so that for a portion of its length it lies above the normal surface of this portion of the pin and hence comes into frictional contact with the hole in which the pin is pushed and retains the pin frictionally in position. In Fig. 5 is shown a modification of the pin in which the entering end of the pin is bored longitudinally at 262 and transversely at 264. A plunger 266 having a wedge-shaped end and backed up by a spring 268 is located in the longitudinal bore 262 and a transverse plunger 270 is located in the transverse hole 264, said plunger having a V-shaped notch which is engaged by the wedge end of the plunger 266. The plunger 270 has a rounded end which extends on one side of the pin beyond the normal surface of the pin, and as the pin is pushed into its hole the plunger 270 will be moved transversely of the pin against the pressure of the plunger 266 which will maintain outward pressure of the plunger 270 and hold it in frictional contact with the hole to retain the pin frictionally in position.

Having thus described my invention, what I claim as new and desire to secure by Letters Patent of the United States is:

1. In a machine of the class described, the combination of a gripping device, a shoe support between which and the gripping device there is relative movement of approach and separation, means for relatively actuating the gripping device and the support to tension the upper over the last, means for securing the upper, means for maintaining a space between the gripper and shoe bottom prior to the movement of separation of the support and gripping device, and means operated by such movement of separation to restore the parts to initial position. 75
  2. In a machine of the class described, the combination of wiping means, means to seize the upstanding margin of the upper at the heel portion of a shoe and to tension it over the shoe bottom, means for securing the tensioned upper, means for maintaining the seizing means out of the way of the shoe during withdrawal of the shoe to prevent the secured upper from being torn loose by contact with the seizing means, and means operated by withdrawal of the shoe to restore the seizing means to initial position. 80
  3. In a machine of the class described, the combination of means for working over and securing in assembled relation upon a last the upstanding margin of an upper at the heel portion thereof, means for maintaining the overworking means out of contacting relation with the overworked upper during withdrawal of the shoe, and means operating as an incident to such withdrawal to restore the overworking means to initial position. 85
  4. In a machine for working an upper over a last, the combination of a wiper, a work support movable toward and from the wiper parallel to its plane of operation, means to impart to the wiper a wiping and a lifting movement, means to hold the wiper lifted, and means operated by movement of the work support to restore the wiper to wiping position. 90
  5. In a machine of the class described, the combination of a wiper, means for advancing and lifting the wiper, means for supporting the wiper in raised position, a work support movable toward and from the wiper, and operative connections between the work support and the wiper for releasing the wiper supporting means by movement of the work support away from the wiper. 95
  6. In a machine of the class described, the combination of a wiper movable over a shoe bottom, means for operating the wiper to wipe the upper over the shoe bottom and then raise it away from the shoe bottom, a latch to hold the wiper in raised position, a shoe support movable toward and from 100
- the wiper, and connections between the shoe support and the latch to release the latch when the work support is moved away from the wiper.
7. In a machine of the class described, the combination of a wiper, means for advancing and raising the wiper, a work support movable toward and from the wiper, means to hold the wiper in raised position, and means controlled by the work support for releasing the holding means. 105
  8. In a machine of the class described, the combination of a wiper for wiping an upper over a last, a gripper, means for operating said wiper and gripper to tension and lay into wiped position a portion of the upper and move away from the upper, means for securing the upper after it is wiped, a work support, means to hold the gripper away from the upper, and connections between the gripper and the work support to release the gripper upon movement of the work support. 110
  9. In a machine of the class described, the combination of a gripping device, a shoe support movable into and out of operative relation to the gripping device, means for operating the gripping device to tension the upper over a shoe on the support and for raising the gripper, means for securing the upper, means for maintaining the gripper away from the shoe bottom, and means operated by movement of the shoe support out of operative relation to the gripper to restore the parts to initial position. 115
  10. In a machine of the class described, the combination of a gripper, means for advancing and lifting the gripper, means for supporting the gripper in raised position, a work support movable toward and from the gripper, and operative connections between the work support and the gripper for releasing the gripper supporting means by movement of the work support away from the gripper. 120
  11. In a machine of the class described, the combination of a gripper movable over a shoe bottom, means for operating the gripper to tension the upper over the shoe bottom and then raise it away from the shoe bottom, a latch to hold the gripper in raised position, a shoe support movable toward and from the gripper, and connections between the shoe support and the latch to release the latch when the work support is moved away from the gripper. 125
  12. In a machine of the class described, the combination of a gripper, means for advancing and raising the gripper, a work support movable toward and from the gripper, means to hold the gripper in raised position, and means controlled by the work support for releasing the holding means. 130
  13. In a machine of the class described, the combination of means for working an upper over a last, a gripper, means for operating said wiper and gripper to tension and lay into wiped position a portion of the upper and move away from the upper, means for securing the upper after it is wiped, a work support, means to hold the gripper away from the upper, and connections between the gripper and the work support to release the gripper upon movement of the work support. 135

upper over a last including a wiper and gripper, means for operating said overworking means to tension into wiped position a portion of the upper and move away from the upper, means for securing the upper after it is wiped, a work support, means to hold the over-working means away from the upper, and connections to the work support to release the over-working means by movement of the work support.

14. A machine of the class described having, in combination, a shoe support movable toward and from the machine and movable vertically, a gripper relatively to which the shoe is positioned with the gripper jaw against the shoe bottom, means for operating the gripper to tension the upper and lay it against the shoe bottom, means for securing the upper, and means for relatively operating the gripper and shoe support to prevent the secured upper from catching on the gripper when the support is moved out of the machine.

15. In a machine for assembling an upper upon a last preparatory to lasting, the combination of a carrier movable over the last and movable vertically, a wiper on the carrier, a gripper mounted on the carrier and co-operating with the wiper to lay a portion of the upper over the last bottom, means for securing the upper after treatment by the gripper and wiper, and means for holding the gripper closed when the wiper is raised and retracted to prevent the upper from catching on the gripper when the shoe is withdrawn.

16. In a machine of the class described, the combination of a wiper for wiping portions of an upper over a last, a gripper co-operating with the wiper to tension the upper and open after its tensioning action, means for securing the wiped over upper, and means for closing the gripper after the securing operation to prevent the gripper from catching on the upper and tearing it loose when the shoe is withdrawn.

17. In a machine of the class described, the combination of a combined wiper and gripper, means acting to cause the gripper to seize the upper and to release it after it has been carried over the shoe bottom, means operating to lift the wiper and gripper to tension the upper, then to lower the wiper and gripper and carry the stock over the shoe bottom, means to secure the upper while the wiper is in contact with the shoe, and means to close the gripper again to prevent the secured upper from catching on the gripper when the shoe is withdrawn after the upper has been secured.

18. In a machine of the class described, the combination of shoe holding means, means to seize and tension the upper, means for causing said seizing means to carry the seized upper over upon the shoe

bottom, means to secure the upper in place, means for releasing the seizing means and raising it above the shoe, means to close the seizing means after it is raised, means to release the shoe, and means to restore the seizing means to normal upper seizing position.

19. In a machine of the class described, the combination of means to seize the upstanding margin of the upper at the heel portion of a shoe and to tension it over the shoe bottom, means for securing the tensioned upper, means for moving the seizing means away from proximity to the upper, and means acting automatically to prevent the secured upper from being torn loose by contact with the seizing means when the shoe is withdrawn from the machine.

20. In a machine of the class described, the combination of means for working over and securing in assembled relation upon a last the upstanding margin of an upper at the heel portion thereof, means for lifting and maintaining the overworking means out of contacting relation with the overworked upper during withdrawal of the shoe from proximity to the overworking means, and means acting thereafter to restore the overworking means to working position.

21. A machine of the class described having, in combination, a shoe support movable toward and from the machine, a gripper relatively to which the shoe is positioned with the gripper jaw against the shoe bottom, means independent of movement of the shoe support for operating the gripper to tension the upper and lay it against the shoe bottom, means for securing the upper, and power means for relatively operating the gripper and shoe support to prevent the secured upper from catching on the gripper when the support is moved away from the machine.

22. In a machine for assembling an upper upon a last preparatory to lasting, the combination of a carrier movable over the last and movable vertically, a wiper on the carrier, a gripper mounted on the carrier and gripper operating means co-operating with the wiper to cause the gripper to seize a portion of the upper and lay it over the last bottom, release it and move away from the last bottom, means for securing the upper after treatment by the gripper and wiper, and means to close the gripper when it is raised to prevent the upper from catching on the gripper when the shoe is withdrawn.

23. In a machine of the class described, the combination of a wiper, means for operating the wiper to cause it to wipe portions of an upper over a last, then rise and return at a distance from the shoe bottom, a gripper co-operating with the wiper to tension the upper, means to open the gripper after its tensioning action, means for securing the wiped over upper, and means for closing the

- gripper during the return movement of the wiper to prevent the gripper from catching on the upper and tearing it loose.
24. In a machine of the class described, the combination of a combined wiper and gripper, means acting to cause the gripper to seize the upper and later to release it, means acting to lift the wiper and gripper to tension the upper, then to lower the wiper and gripper while carrying the stock over the shoe bottom, then raise the gripper and retract it after the upper has been released, means to secure the upper while the wiper is in contact with the shoe, and means to close the gripper again during its retracting movement to prevent the secured upper from catching on the gripper when the shoe is withdrawn after the upper has been secured.
25. In a machine of the class described, the combination of shoe holding means, means to seize and tension the upper in a plane perpendicular to the last bottom, means for giving said seizing means an orbital path of movement to cause said seizing means to carry the seized upper over upon the shoe bottom and return out of contact with the shoe bottom, means to secure the upper in place, means for releasing the seizing means after its tensioning action, means to close the seizing means during its return movement to normal position, and means to release the shoe.
26. A machine for assembling and securing in assembled relation the upper of a shoe upon a last preparatory to lasting, having, in combination, a combined wiper and gripper operating to seize, tension and overlay a portion of the upper over the last bottom, means to secure the upper in overlaid position, means to lift and retract the wiper after its function is completed, and means for causing the gripper to close during its retracting movement to avoid catching of the gripper upon the secured upper during withdrawal of the shoe from the machine.
27. A machine for assembling and securing in assembled relation an upper of a shoe upon a last preparatory to lasting, having, in combination, a wiper, a gripper pivoted to the wiper and co-operating with the wiper to seize the upper, means to cause the gripper to close, uplift, lay the upper over the shoe bottom, release the upper and then rise and return to initial position, an offset arm on the gripper, and a relatively fixed arm to engage the offset arm and cause the gripper to close during the retracting movement of the gripper so that the gripper, when it reaches initial position, will be rearwardly beyond the edge of the portions secured and the shoe may be withdrawn without catching the secured upper upon the gripper.
28. In a machine of the class described, the combination of a tacker arranged for movement over the shoe bottom in a position spaced above the shoe bottom and movable toward the shoe bottom, exposed tack fingers on the tacker, and means carried by the tacker for engaging the work as the tacker moves toward the shoe bottom to avoid actual contact of the tack fingers with the work and to leave the tack fingers free to be separated by passage of the tack and driver between them.
29. A machine for securing parts of boots and shoes in assembled relation upon a last preliminary to lasting, having, in combination, means for holding an upper and last in assembled relation, tacking means, means for moving the last and tacking means relatively to position the tacking means over the heel seat, means acting in consequence of said relative movement to position the tackers inside the upper and over the counter flange, and means for pressing the counter flange against the shoe bottom prior to the action of the tackers.
30. A machine for securing parts of boots and shoes in assembled relation upon a last preliminary to lasting, having in combination, tackers, means for relatively moving the tackers and shoe to position the tackers over the shoe bottom, means for laterally moving the tackers outwardly relatively to a point between them to position them at predetermined distances from the last edge, and means arranged to press upon the shoe bottom and prevent actual contact of the tackers with the shoe bottom.
31. A machine for securing parts of boots and shoes in assembled relation upon a last preparatory to lasting, having, in combination, tackers positioned at the rear of the shoe comprising tack holding means, means for moving the shoe and tackers relatively to position the tackers over the shoe bottom out of contact therewith, means for moving the tackers toward the shoe bottom, and means acting to press positively against the shoe bottom adjacent to the tackers prior to the insertion of the tacks.
32. A machine for securing parts of boots and shoes in assembled relation upon a last preliminary to lasting, having, in combination, tackers, means for relatively moving the tackers and shoe in the direction of the longitudinal median line of an end of the shoe to position the tackers over the shoe bottom, means operating during such movement for separating the tackers to position them at predetermined distances from opposite side edges of the last, and means arranged to press the shoe material against the last bottom prior to the action of the tackers in securing the material.
33. In a machine of the class described, the combination of a gripper, tackers mov-

able over the shoe bottom out of contact therewith, and means operated by opening movement of the gripper for causing the tackers to move toward the work.

34. In a machine of the class described, the combination of a tacker arranged for movement over a shoe bottom out of contact therewith and movable into contact with the shoe bottom, a gripper mechanism, and means operated by the gripper mechanism for moving the tacker toward the shoe bottom prior to the tacking operation.

35. In a machine of the class described, the combination of a gripper, means for operating the gripper, tackers movable over the shoe bottom out of contact therewith, and connections between the tackers and the gripper operating means for causing the tackers to move into substantial contact with the work prior to the tack driving operation.

36. In a machine of the class described, the combination of a tacker arranged for movement over a shoe bottom out of contact therewith and movable into contact with the shoe bottom, a gripper, means for operating the gripper, and means operated by the gripper operating means for moving the tacker positively into substantial contact with the shoe bottom prior to the tacking operation.

37. A machine for securing the parts of boots and shoes in assembled relation upon a last preliminary to lasting, having, in combination, tackers positioned at the rear of a shoe comprising tack holding fingers and tack drivers, means for moving the tackers and shoe relatively to position the tackers over the shoe bottom out of contact therewith, and means for positively moving the tackers toward the shoe bottom.

38. A machine for securing parts of boots and shoes in assembled relation upon a last preparatory to lasting, having, in combination, tackers positioned at the rear of the shoe comprising exposed tack holding fingers and tack drivers, means for moving the tackers and shoe relatively to position the tackers over the shoe bottom out of contact therewith, means for moving the tackers toward the shoe bottom, and means in advance of the tackers to engage the shoe bottom and prevent actual contact of the tack fingers with the shoe bottom so that the tack fingers are free to separate when the tack is driven.

39. A machine for securing parts of boots and shoes in assembled relation upon a last preparatory to lasting, having, in combination, a gripper, operating means therefor, tackers positioned at the rear of the shoe comprising tack holding means, means for moving the tackers to position the tackers over the shoe bottom out of contact therewith, and means operated by the gripper operating means to move the tackers positively toward the work.

40. In a machine for assembling parts of boots and shoes upon their lasts preparatory to lasting, the combination of means for exerting substantially positive pressure upon the rear end of a shoe adjacent to the edge 70 of the counter nearest the crown of the last, means for wiping the upper over the heel seat, means for delivering a blow upon the rear end of the shoe adjacent to the heel seat to seat the counter against the end of the 75 last at that point, and means for thereafter securing the wiped over upper to the heel seat.

41. In a machine for assembling parts of boots and shoes upon their lasts preparatory 80 to lasting, the combination of means for exerting substantially positive pressure upon the rear end of the shoe adjacent to the edge of the counter nearest the crown of the last, means for wiping the upper over the heel 85 seat, means for securing the upper to the rear end of the last adjacent to the heel seat, means acting simultaneously by impact to seat the counter against the last, and means for thereafter securing the wiped over upper 90 to the heel seat.

42. In a machine for assembling parts of boots and shoes upon their lasts preparatory to lasting, the combination of means for securing the upper and counter to the rear 95 end of the last adjacent to the edge of the counter most distant from the last bottom, means for tensioning the upper upwardly from the point secured and wiping it over the heel seat of the last, means for delivering 100 a blow to the rear end of the shoe adjacent to the heel seat to seat the counter against the last, and means for thereafter securing the counter and upper to the innersole.

43. In a machine for assembling parts of boots and shoes upon their lasts preparatory 105 to lasting, the combination of means for securing the upper and counter to the rear end of the last adjacent to the edge of the counter most distant from the last bottom, 110 means for tensioning the upper upwardly from the point secured and wiping it over the heel seat of the last, means for exerting pressure on the upper adjacent to the heel seat to force the counter against the last, 115 and means for thereafter securing the wiped over upper and counter to the innersole.

44. In a machine for assembling parts of boots and shoes upon their lasts preparatory 120 to lasting, the combination of means for securing the upper and counter to the rear end of the last adjacent to the edge of the counter most distant from the last bottom, means for tensioning the upper upwardly from the point secured and wiping it 125 over the heel seat of the last, means for driving a tack in the counter of the shoe at the rear end of the heel seat and at the same time exerting an outward thrust upon the counter to seat it against the last, and means 130

for thereafter securing the upper and counter to the innersole.

45. In a machine of the class described, the combination with upper wiping and securing means and a shoe support, of a hook having a face acting on the shoe support to draw the shoe support into the machine different distances according to the position of the hook and to hold the support positively

10 against outward movement, means for applying to the hook substantially constant pressure irrespectively of the position assumed by the hook, and a power operated cam for controlling the action of said pressure applying means which acts to cause said pressure to be applied gradually.

46. In a machine of the class described, the combination with upper wiping and securing means, an abutment for the shoe, and 20 a shoe support, of a member having a cam face acting on the shoe support to press the shoe against the abutment and to draw the shoe support into the machine different distances according to the length of the last

25 and to hold the support positively against outward movement, means for applying to the cam member substantially constant actuating force, and means for causing said force to be applied gradually.

30 47. In a machine of the class described, the combination with upper wiping and securing means and a shoe support, of a hook having a cam-shaped face acting on the shoe support to draw the shoe support into the machine different distances according to the position of the hook, and to hold the support positively against outward movement, a long helical spring for applying to the hook substantially constant pressure irrespectively of the position of the hook, and a power operated slow acting cam for controlling the action of the spring to cause said spring to act gradually.

48. A machine for securing parts of boots 45 and shoes in assembled relation upon a last preparatory to lasting, having, in combination, pressers arranged to engage the sides of the rear part of a shoe, springs for operating the pressers, and means for adjusting the tension of each of the springs comprising a collar having connection with one presser and a second collar connected to the spring, said collars having interengaging ratchet teeth on their adjacent faces.

50 49. A machine for securing parts of boots and shoes in assembled relation upon a last preparatory to lasting, having, in combination, a presser arranged to engage the side of the rear part of a shoe, a collar having connection with the presser, a second collar, a spring connected to the second collar, and interengaging teeth on the adjacent faces of the collars so that the tension of the spring may be varied by turning the second collar 60 relatively to the first.

50. A machine for securing parts of boots and shoes in assembled relation upon a last preparatory to lasting, having, in combination, rock shafts carrying pressers for engaging opposite sides of the rear part of a shoe, torsion springs on said shafts anchored at one end to a frame, loose collars on the shafts connected to the opposite ends of the springs, collars fixed on the shafts adjacent to the loose collars, and interengaging ratchet teeth on the adjacent faces of the collars so that the tension of the springs may be adjusted by relative rotation of the fixed and loose collars.

51. A machine for securing parts of boots and shoes in assembled relation upon a last preparatory to lasting, having, in combination, a heel seat tacker and counter flange tackers movable together from a position at the rear of the shoe lengthwise of the shoe 85 into tacking position, and means arranged for adjustment to vary the position of the flange tackers relatively to the heel seat tacker lengthwise of the shoe.

52. A machine for securing parts of boots and shoes in assembled relation upon a last preliminary to lasting, having, in combination, means for holding an upper and last in assembled relation, a tacker for inserting a tack at the rear end of the heel seat to 90 secure the upper and counter to the innersole, counter flange tackers, means for moving the last and tackers relatively to position the tackers over the heel seat, means acting in consequence of said relative movement to 95 position the counter flange tackers inside the upper and over the counter flange, and means permitting adjustment of the counter flange tackers lengthwise of the shoe relatively to the heel seat tacker.

100 53. In a machine for assembling parts of boots and shoes upon their lasts preparatory to lasting, the combination of a tacker including a driver and tack throat movable upwardly and over the shoe bottom and downwardly into tacking position, means for lowering the tack driver to hold a fed tack in the tack throat during said movement of the tacker, and means for then raising and releasing the driver to drive the tack.

110 54. In a machine for assembling parts of boots and shoes upon their lasts preparatory to lasting, the combination of a tacker including a tack passage, a driver and tack fingers, means for feeding a tack to be retained by the fingers, means for moving the tacker upwardly over the shoe bottom and down upon it, means for preventing the tack from bouncing back into the tack passage during such movement of the tacker, and means for driving the tack after movement of the tacker is completed.

120 55. In a machine for assembling parts of boots and shoes upon their lasts preparatory to lasting, the combination of shoe holding

means, a slide to contact with the rear end of the shoe, a tacker, including a driver bar, pivoted to said slide, and a pivot pin for the tacker having its pivot portion uniform in cross-section and constructed and arranged to withstand the continual impact of the driver bar transmitted through said pin to the slide.

56. In a machine for assembling parts of boots and shoes upon their lasts preparatory to lasting, having, in combination, an abutment slide for the shoe, a tacker pivoted to said slide for adjustment of the position of

the tack relatively to the slide, a pivot pin forming said pivot, said pin having a flanged 15 head and being formed with its pivot portion uniform in cross-section, a latch engaging said flange to hold the pin in place and permitting the pin when released to be removed without rotation, and a driver bar 20 in the tacker the impact of which is received by the tacker and transmitted through said pin to the abutment slide.

In testimony whereof I have signed my name to this specification.

NORWOOD H. KNOWLTON.
